OSCILLATING LEASE ROD LEVELING
MECHANISMAlbert E. Winslow, Greenville, S. C., assignor to
J. P. Stevens & Co. Inc., Greenville, S. C., a corporation of Delaware

Application August 1, 1950, Serial No. 177,039

15 Claims. (Cl. 139—98)

1

This invention relates to the control of a pair of oscillating lease rods in a loom. It is frequently desirable to provide in a loom a pair of lease rods placed in the warp and mounted to oscillate during the operation of the loom on an axis intermediate of and parallel to the lease rods in order to place intermittent tension on the warps and thus control the placing and positioning of the filling in the woven fabric.

The strain on the warps during such a regular oscillation of the lease rods is momentary; but if the loom be stopped with the lease rods out of level the strain is maintained until weaving is resumed and is apt to result in a permanent change in the warps and a deleterious effect in the required uniformity of the cloth being woven.

The object of the invention is to provide for preventing undue tension upon or the straining of the warps by the lease rods when the loom is stopped.

This matter of preventing undue strain upon the warps is important because a loom customarily stops at or near front center and this term "at front center" as herein employed is to be construed as including a position adjacent front center. When a loom thus stops the lease rods are normally left in a position out of level and thus in a position to place strain upon the warps.

The general rule is that a shed of warps shall be as small as the nature of the work to be done will allow because the strain upon a warp increases approximately as the square of the space passed through in forming the shed. The lease rods oscillate to move each lease rod alternately above and below a neutral position, herein referred to as a level position, where the lease rods have a minimum tensioning effect on the warps and their plane is usually parallel with the warp line running from the whip roll to the breast beam of the loom. The object of the invention is therefore to bring these lease rods to this level position coincidently with the stopping of the loom at front center.

More specifically the invention provides an actuator, preferably in the form of an eccentric, acting during the operation of the loom to effect the oscillation of the lease rods and means actuated upon the stopping of the loom at front center to shift this actuator with respect to its operating means to bring it to a neutral position and thus effect the positioning of the lease rods in level position and thus prevent maintenance of a deleterious strain upon the warps while the loom is stopped.

The nature and objects of the invention will 55

2

appear more fully from the accompanying description and drawings and will be particularly pointed out in the claims.

Since the invention only has to do with the lease rods of a loom and the means for operating and controlling the operation of the lease rods and as the general construction and operation of a loom, so far as this invention is concerned, is well known and familiar to those skilled in the art, it is only necessary for a disclosure of the present invention to illustrate and describe a preferred embodiment of the invention and only so much of those portions of a loom as is necessary for the purpose.

15 In the drawings:

Fig. 1 is a top plan view of a portion of one side of a loom equipped with a preferred construction of the invention;

Fig. 2 is a side elevation of the parts shown in 20 Fig. 1;

Fig. 3 is a view principally in vertical transverse section taken on the line 3—3 of Fig. 2;

Fig. 4 is a side elevation and partially broken away of the mechanism directly concerned with 25 the oscillation of the lease rods, showing them in one extreme position;

Fig. 5 is a view similar to Fig. 4 with the lease rods in level position; and

Fig. 6 is another similar view showing the lease 30 rods in the opposite extreme position from that of Fig. 4.

Portions of one side frame of a loom are indicated at 1, and portions of the opposite side frame at 2. The loom is shown as having the usual main shaft 3 with the hand wheel 4 and driven from any suitable source of power; and also the usual cam shaft 5. The various means employed in looms for stopping the loom because of a mis-positioned shuttle, warp breakage, etc., uniformly act to stop the loom at or near front center. When this takes place the usual shipper handle 6 found on the loom is given a sudden rocking movement on its fulcrum 7. While in the broader scope of the present invention any means operated upon the stopping of the loom at or near front center may be employed as the controlling means, such a shipper lever is conveniently employed because it is to be found on practically all looms and has a quick positive movement when the loom stops.

The pair of lease rods 8 and 9 are shown in their usual position at the rear of the loom extending between the warps 10. These lease rods are shown mounted near each end in clamping blocks 11 and 12 provided with clamping screws

55

13. These clamping blocks are provided with aligned shaft sections 14 and 15. The axis of these shaft sections 14 and 15 extends midway between the lease rods and parallel thereto and the lease rods oscillate on this axis. The shaft section 14 extends into a suitable bearing block 16 mounted on the side frame 2 and the shaft section 15 into a similar bearing block 17 mounted on the side frame 1. These bearing blocks, as indicated in the block 17, are preferably provided with suitable ball bearings 18 for the shaft section.

It will thus be seen that by the oscillation of the shaft 14, 15, the lease rods oscillate on an axis intermediate of and parallel to the lease rods and act to place an intermittent tension on the warps. While it is a comparatively simple matter to provide for a regular oscillation of the lease rods any such mechanism will usually shift the lease rods out of level when the loom stops at front center and thus produce an undue strain on the warps and a deleterious effect on the fabric being woven. This difficulty is obviated in the present invention by providing novel means for oscillating the lease rods and so controlling the same that when the loom stops at front center the lease rods are automatically brought to level position where the strain on the warps is at a minimum.

In the preferred form illustrated the invention provides an actuator, such as an eccentric, for oscillating the lease rods and means for shifting the position of this actuator or eccentric upon the stopping of the loom to effect the movement of the lease rods to level position.

The specific mechanism illustrated is chiefly enclosed in a casing 19 secured by bolts 20 to the side frame 1 opposite the end of the shaft section 15. In this casing is journaled a shaft 21 driven during the operation of the loom as by a sprocket chain 22 extending around a sprocket wheel 23 on the cam shaft 5 to a sprocket wheel 24 on the shaft 21. An idler 25, supported from the casing 19, serves to keep the sprocket chain taut. A cover 26 extends over the sprocket wheel 24, the idler 25, and a large portion of the sprocket chain and is bolted to the casing 19 at 27.

An eccentric 30 on the thus driven shaft 21 operates a link 31 pivoted at 32 at its upper end to an arm 33 secured to the shaft section 15. Consequently, as the eccentric is rotated the shaft section 15 is oscillated and therewith the lease rods given the required oscillating movement.

Connecting means are provided extending from the driven shaft 21 to this eccentric which act to effect the rotation of the eccentric with the shaft when the shaft is driven during the operation of the loom and means are provided for shifting this eccentric rotarily of the shaft to bring it to the position required, in turn to bring the lease rods to level position when the loom is stopped. In the preferred construction illustrated for this purpose the eccentric is journaled on the shaft but not keyed thereto, a gear is mounted on and keyed to the shaft, a second gear is journaled on the shaft and keyed to the eccentric, and a train of gears are provided intermediate these two gears with means for maintaining the gears of said train in fixed position during the operation of the loom to cause the driven shaft to rotate the eccentric. Then when the loom stops at front center means act to effect a change in the relative position of

the gears and this train and thus to shift the eccentric on the driven shaft and position the lease rods in level position.

As illustrated the gear 34 is keyed to the driven shaft 21, the gear 35 is keyed to the eccentric 30 and thus rotates therewith. A stub shaft 36 has journaled thereon a gear 37 meshing with the gear 34. A gear 38 meshing with the gear 35 is also journaled on the stub shaft 36 and is keyed to the gear 37. Thus it will be seen that with the stub shaft 36 in fixed position when the driven shaft 21 is driven that the eccentric will be operated to effect the oscillation of the lease rods.

In the construction illustrated the stub shaft 36 is mounted in a rocker arm 39 journaled on a hub 40 projecting from the casing 19 concentric with the shaft 21. This rocker arm at its upper end normally abuts against an adjustable stop 41, shown as a screw, mounted in the casing 19. If now the rocker arm be swung away from this stop it effects a change in the relative position of the gears of the train and acts to shift the eccentric rotarily on the driven shaft. Consequently by properly proportioning the ratio of the gears and the extent of movement of the rocker arm the eccentric may readily be shifted to a neutral position bringing the lease rods to level position.

Since, as noted, a loom commonly stops at front center suitable means are provided acting upon the stopping of the loom to effect this change in position of the eccentric and in the preferred construction illustrated, as already noted, the movement of the shipper handle which takes place when the loom is stopped is conveniently utilized for this purpose. A transmitting rod 42, 43, is pivotally connected at its rear end to a projection 44 on the rocker arm 39 and at its

front end to the upper arm of a lever 45 fulcrumed at 46 on a bracket 47 mounted on the loom frame 1. Another transmitting rod 48 connects the lower arm of the lever 45 to the lower end of the shipper handle 6. All these connections are made suitably adjustable as illustrated.

Consequently, when the shipper handle 6 rocks upon the stopping of the loom, by means of these connections, the rocker arm 39 is swung away from the stop 41. Since, when the loom stops at front center, the eccentric will be at one or the other of its extreme limits of movement it is necessary to shift the eccentric rotarily on the driven shaft through 90° to bring it to neutral position and effect the leveling of the lease rods.

But to swing the rocker arm through 90° is usually inconvenient and consequently the ratio of the gears is made such as to cause the movement of the rocker arm through a much less angle to shift the eccentric through 90°. In the construction illustrated the gears 35 and 37 are made of the same diameter, the gears 34 and 38 are of the same diameter, and the latter diameter is about 1 1/4 that of the former. With this ratio a swinging movement of the rocker arm 39 away from the stop 41 through an angle of about 45° will shift the eccentric on the shaft 21 through an angle of 90°.

It is desirable to lock the rocker arm in its normal position against the stop 41 during the operation of the loom and suitable means are provided for this purpose and are unlocked upon the stopping of the loom. This is conveniently secured by the construction illustrated in which the section 43 of the transmitting rod telescopes in

the section 42, the latter for that purpose having adjustably secured thereto a socketed portion 49. A locking element in the form of a bell crank lever 50 is pivotally mounted at 51 on the section 43 with its lower arm having a projection 52 fitting into a notched element 53 mounted at 54 on the loom frame. The upper end of this bell crank lever 50 is provided with a roller 55 opposite a cam face 56 on the socket 49. When, therefore, the loom stops and the lever 45 is rocked the section 43 of the transmitter rod acts first to cam the bell crank lever 50 out of the notched element 53 to unlocked position and then as the telescoping action takes place the section 42 seats against the end of the section 43 and further movement swings the rocker arm 39 to the required position.

In Figs. 4 and 6 the elements are shown in the position occupied when the loom is running and consequently the shaft 21 is being driven. In Fig. 4 the eccentric 30 is at the limit of its downward movement, thus raising the lease rod 8 to its uppermost position and the lease rod 9 to its lowermost position. In Fig. 6 the eccentric is at the upper limit of its movement thus lowering the lease rod 8 to its lowermost position and the lease rod 9 to its uppermost position. In Fig. 5 the parts are in the position occupied when the loom has stopped and consequently the shaft 21 is no longer rotating. The transmitter rod 43 has swung the rocker arm 39 away from the stop 41 through an angle of substantially 45° and brought the eccentric to neutral position and consequently the lease rods to level position. It will be seen that no matter whether the loom stops with the parts positioned as shown in either Fig. 4 or Fig. 6 the eccentric will be shifted through 90° and brought into a neutral position with the eccentric either in the position shown as in Fig. 5 or in a position directly opposite.

Having thus described the invention, what is claimed as new, and desired to be secured by Letters Patent, is:

1. In a loom the combination of a pair of lease rods mounted to oscillate on an axis intermediate thereof and parallel thereto, means for oscillating the lease rods on said axis during the operation of the loom, and an element moved when the loom stops at front center acting upon said means to position the lease rods in level position.

2. In a loom the combination of a pair of lease rods mounted to oscillate on an axis intermediate thereof and parallel thereto, an actuator to effect oscillation of the lease rods on said axis, means acting to operate the actuator during the operation of the loom, and means moved when the loom stops at front center acting to shift said actuator with respect to its operating means to position the lease rods in level position.

3. In a loom the combination of a pair of lease rods mounted to oscillate on an axis intermediate thereof and parallel thereto, an eccentric, means for rotating the eccentric during the operation of the loom to effect oscillation of the lease rods on said axis, an element moved when the loom stops at front center acting thereupon to shift the eccentric on its axis of rotation to position the lease rods in level position.

4. In a loom the combination of a pair of lease rods mounted to oscillate on an axis intermediate thereof and parallel thereto, a shaft driven during the operation of the loom, an eccentric journaled on said shaft, means acting upon rotation of the eccentric to effect oscillation of the

lease rods on said axis, a rocker arm mounted concentric the driven shaft, a stub shaft on said rocker arm extending parallel to the driven shaft, a gear on and keyed to the driven shaft, a second gear journaled on the driven shaft and keyed to the eccentric, a third gear and a fourth gear keyed together and journaled on the stub shaft with the first and third gears intermeshing and the fourth and second gears intermeshing, and a stop engaging the rocker arm, the said elements acting upon rotation of the driven shaft to rotate the eccentric.

5. In a loom the construction defined and operating as in claim 4, together with means acting when the loom stops at front center to swing the rocker arm away from the stop and shift the eccentric on the driven shaft to position the lease rods in level position.

6. In a loom the construction defined and operating as in claim 4, together with an element moved when the loom stops at front center acting to swing the rocker arm away from the stop and shift the eccentric on the driven shaft to position the lease rods in level position.

7. In a loom the construction defined and operating as in claim 4, in which the ratios of the respective gears cause a movement of the rocker arm through an angle of substantially 45° to shift the eccentric through substantially 90°.

8. In a loom the construction defined and operating as in claim 4, in which the ratios of the respective gears cause a movement of the rocker arm through an angle of materially less than 90° to shift the eccentric through an angle of 90°.

9. In a loom the construction defined and operating as in claim 4, together with means acting when the loom stops at front center to swing the rocker arm away from the stop and shift the eccentric on the driven shaft to position the lease rods in level position, means for locking the rocker arm against movement, and means for unlocking said locking means upon the said stopping of the loom.

10. In a loom the construction defined and operating as in claim 4, together with an element moved when the loom stops at front center acting to swing the rocker arm away from the stop and shift the eccentric on the driven shaft to position the lease rods in level position, means for locking the rocker arm against movement, and means for unlocking said locking means upon said movement of said element.

11. In a loom the construction defined and operating as in claim 4, together with an element moved when the loom stops at front center acting to swing the rocker arm away from the stop and shift the eccentric on the driven shaft to position the lease rods in level position, in which the said element includes a telescoping rod with one section connected to the rocker arm, a cam on the other section, and a locking element on the first section cooperating with the loom frame to lock the rocker arm against movement, the movement of the rod upon the stopping of the loom acting first to telescope the sections and cause the cam to release the locking element and then to swing the rocker arm.

12. In a loom the combination of a pair of lease rods mounted to oscillate on an axis intermediate thereof and parallel thereto, a shaft driven during the operation of the loom, an eccentric journaled on said shaft, means acting upon the rotation of the eccentric to effect oscillation of the lease rods on said axis, a gear on and keyed to the driven shaft, a gear journaled

70

on the driven shaft and keyed to the eccentric, a train of gears intermediate said gears, and means for maintaining the gears of said train in fixed position during the operation of the loom to cause the driven shaft to rotate the eccentric.

13. In a loom the construction defined and operating as in claim 12, together with means acting when the loom stops at front center to effect a change in the relative position of the gears of said train, acting to shift the eccentric on the driven shaft and position the lease rods in level position.

14. In a loom the construction defined and operating as in claim 12, together with a rod moved rectilinearly when the loom stops at front center acting to effect a change in the relative position of the gears of said train, acting to shift the eccentric on the driven shaft and position the lease rods in level position.

5
10
15

15. In a loom the combination of a pair of lease rods mounted to oscillate on an axis intermediate thereof and parallel thereto, a shaft driven during the operation of the loom, an eccentric journaled on said shaft, means acting upon the rotation of the eccentric to effect oscillation of the lease rods on said axis, connecting means extending from the driven shaft to the eccentric acting to rotate the eccentric with the shaft upon rotation of the shaft, and means actuated upon the stopping of the loom at front center acting to operate the connecting means to shift the eccentric rotarily of the shaft.
